UNITED STATES PATENT OFFICE.

CHARLES HARRY FISCHER, OF CINCINNATI, OHIO.

ELECTRIC LAMP.

1,140,893.

Specification of Letters Patent. Patented May 25, 1915.

Application filed March 13, 1915. Serial No. 14,214.

To all whom it may concern:

Be it known that I, CHARLES H. FISCHER, a citizen of the United States, residing at Cincinnati, in the county of Hamilton and 5 State of Ohio, have invented certain new and useful Improvements in Electric Lamps, of which the following is a specification.

My invention relates to electric lamps, especially to such electric lamps as are employed for headlights for automobiles or other vehicles, and has for its object the provision of novel means whereby to focus the electric light-bulb and maintain the bulb 15 in adjusted position.

It is a further object of my invention to provide novel means whereby the electric light-bulb may be manually shifted with relation to the reflector rotatively or axially 20 or by movements which are the sums of said rotative and axial movements, so as to adjust the bulb with relation to the focus of the reflector; further to provide means resiliently acting for retarding said movements; further to provide complementary 25 surfaces, one of which is shiftable with relation to the other, having coacting depressions and protuberances, the depressions in one of said surfaces merging into each other 30 or being crossingly arranged for maintaining the light-bulb in adjusted position; further to provide resilient means whereby said surfaces are held toward each other; further to provide a part with which the 35 bulb has connection and a part in which said last-named part has rotative and axial movements so arranged as to limit said axial movement and when at such limit of axial movement to prevent relative rotation between said parts; and the invention will be 40 further readily understood from the following description and claims, and from the drawings, in which latter:

Figure 1 is an axial section of an electric lamp embodying my invention. Fig. 2 is a perspective view showing the means for attaching and focusing the electric light-bulb, the parts being shown in separated relation. Fig. 3 is a side elevation of my improved device in assembled relation, the reflector and casing being partly broken away. Fig. 4 is 45 an axial section of the same taken on a line corresponding to the line 4—4 of Fig. 5, the socket-member being in rear position. Fig. 5 is a front elevation of the central portion 50

of my improved device, the light-bulb being removed. Fig. 6 is an axial section of my improved device, partly broken away, taken on the line 6—6 of Fig. 5, the socket-member being shown in rear position with its limiting stop in frictional contact with the wall of its guide. Fig. 7 is a cross-section of my improved device taken on a line corresponding to the line 7—7 of Fig. 3. Fig. 8 is a perspective view of the spring-member 60 showing the contact-surface of its shoe; and, Fig. 9 is an enlarged cross-sectional detail of the socket-member.

My present invention is an improvement on the device shown, described and claimed 70 in my Patent No. 1,114,976, dated October 27, 1914.

I do not herein claim the means for supporting and insulating the central electric terminal post of the electric connector, having shown, described and claimed the same in an application for patent on electric connectors, filed July 17, 1914, Serial No. 851,581.

The casing of the lamp is shown at 11. 80

12 is the reflector, exemplified as a parabolic reflector, secured to the casing by screws 13 for forming the body of the lamp.

The front closure is shown at 14, exemplified as a door provided with a glass 15. The door is arranged to be suitably mounted on the body, as by hinges 16, or the casing, reflector and door are suitably connected together in other manner, preferably so that the front glass 14 is releasable, in order to obtain access to the electric light-bulb, which is shown at 17, by means of which the manipulation is effected, in the present exemplification, for focusing the light-bulb in the reflector. The reflector is received within 90 the casing, there being a space 18 between the reflector and casing.

My invention is also applicable in relations in which the adjustment of the electric light-bulb to focus is accomplished from the outside of the casing, an example of which is illustrated in my application for Letters Patent on improvements in electric lamps, filed March 13, 1915, Serial No. 14,215, executed of even date herewith, in which latter 100 application claims are also directed to such structure.

A socket-member is provided, to which the electric light-bulb is arranged to be secured, this socket-member being instanced 110

as a socket-tube 21 received in a central rear aperture 22 of the reflector. A flange 23 acts to support the socket-member in the line of the axis of the reflector. This flange 5 exemplifies a lamp-member and is shown on a flange-piece 24 suitably rigidly secured to the reflector, as by soldering. The socket-member has plug attaching means at one of its ends, exemplified as at its forward end, 10 shown as bayonet slots 25 in the wall of the socket-member arranged for receiving the pins 26 of the plug 27 exemplified as the plug of the electric light-bulb. The outer periphery of the socket-member and the inner periphery of the flange or lamp-member therefore, are preferably annular and preferably arranged so that the socket-member may have rotary or axial movement, or a movement which is the sum of these two movements 15 in said flange or lamp-member, a resilient part being provided with relation to which said socket-member has movement, the latter member and said socket-member having complementary coacting surfaces arranged 20 for permitting said movement of said socket-member and holding said socket-member in adjusted positions. Thus the socket-member is provided with protuberances 31 and depressions 32, the depressions extending in 25 a plurality of directions crossing each other for forming the protuberances. The coacting member for said surface is shown as a shoe 33, which is received through an opening 34 in the flange 23, and has an inner 30 end provided with protuberances 36 and depressions 37 coacting with the protuberances 31 and depressions on said socket-member.

The shoe is mounted on a spring 38, shown 35 as a band-spring, curved to be received about the flange, the band preferably extending more than half way around the flange, so that it will be retained on said flange by its spring pressure and arranged to be releasably received thereabout. The end of 40 the spring is curved outwardly as shown at 39, so that the spring may be readily pushed about the flange. The spring urges the shoe 33 toward the socket-member for continuously maintaining resilient contact between 45 said shoe and said socket-member. A plurality of protuberances on one of said coacting position-maintaining parts is preferably received in a plurality of the depressions of the other of said parts so as to maintain 50 said parts in relatively adjusted relations. Proximate protuberances and depressions are closely adjacent to each other for providing minuteness of focal adjustment.

A terminal post 41 is arranged to be 55 pressed toward the light-bulb by a spring 42. The post has axial movement in a bushing 40 in an insulating washer 43, clamped to the socket-tube 21 by a cap 44 screwed about the outer threaded end of the socket-tube. The 60 plug of the light-bulb is arranged to be re-

ceived in its socket, so that, in forming the bayonet connection therewith, its terminal 65 will press the post 41 axially for making good electric connection therewith, the spring 42 resisting this axial movement. 70

The holding properties of the spring 38 and the position-retaining means for the socket-member will ordinarily not be sufficient to counteract the manual force exerted 75 in rotary and axial lines in connecting the plug with the socket-member, in consequence of which the socket-member will be pushed axially by the plug. This axial movement is, in the present exemplification, a rearward movement. This axial movement of the 80 socket-member is limited by providing it with a stop, shown as a lip 46, which is arranged to be received in a recess 47 at the inner end of the guide in which the socket-member moves, a plurality of these recesses 85 being shown. (See Figs. 3, 4 and 5). The recesses are preferably shallow so as to arrest the lengthwise movement of the lip. When the lip is received in a recess, rotation of the socket-piece will also be limited, whereby 90 a turning of the light-bulb in its socket can be effected for causing the pins to be received in or removed from the lateral portions of the bayonet slots. A slight inward urging 95 of the socket-member, after connection of the light-bulb therewith, will bring the lip out of the recess for again permitting the turning of the socket-member.

If desired, the portion of the lip 46 proximate to the lamp-member, shown as the rear portion, may be made tapering, as shown at 100 48, whereby a wedging of the socket-member in its guide will be effected by contact of the rear end of the lip with any portion in the circumference of the forward edge of the 105 guide not recessed as hereinbefore mentioned, when the socket-member is moved rearwardly. (See Fig. 6). The forward movement of the socket-member will be limited by contact of the cap 44 with the rear end of the flange 23. The axial, rotative, and combined axial and rotative movements obtainable in my improved device afford 110 ease of manual manipulation of the light-bulb, the parts being so arranged however as to afford great resistance to unintentional shifting after adjustment.

The arrangement of my improved device 115 whereby provision is made for imparting an axial movement, and a rotative movement, and a movement which is the sum of both said movements, to the light-bulb, that is to say, for adjusting said light-bulb in any direction along or about the line of the principal axis of the reflector, enables me 120 to adjust the light-bulb in such manner as to accommodate the position of the filament in the light-bulb to the reflector for placing the filament, for instance, in a line up or down or sidewise, or presenting any portion 125 130

of the filament toward any portion of the reflector for producing the best light results, and for adjusting the filament into the focus of the reflector, whereby the most effective results may be obtained.

Having thus fully described my invention, what I claim as new and desire to secure by Letters Patent, is:

1. In an electric lamp, the combination 10 with a reflector, of a lamp-member, a socket-member guided by the latter, said socket-member having thereon retardent surface-formations extending in a plurality of directions, and a resiliently acting position-retaining part coaxing with said surface-formations, whereby said socket-member is arranged to be moved manually in any direction along or about the line of the principal axis of said reflector and said position-retaining part remaining automatically effective for retaining said socket-member in adjusted position.

2. In an electric lamp, the combination with a reflector, of a socket-member, a lamp-member guiding the latter, a plug for said socket-member, spring-pressed connecting means between said socket-member and plug arranged to be connected by axial and rotative movements of said plug, position-retaining means acting resiliently on said socket-member, whereby said socket-member is arranged to be manually moved in any direction along or about the line of the principal axis of said reflector and said position-retaining means remaining automatically effective for retaining said socket-member in adjusted positions, and a stop for limiting movement of said socket-member in the directions of said axial and rotative movements of said plug during connecting of said plug.

3. In an electric lamp, the combination of a reflector, a lamp-member, a socket-member having movement in said lamp-member in any direction along or about the line of the principal axis of said reflector, and resiliently acting position-retaining means continuously acting operatively between said members, said resiliently acting position-retaining means and socket-member provided with coaxing position-retaining surfaces one of which is formed by alternating protuberances and depressions extending crossingly in a plurality of directions.

4. In an electric lamp, the combination of a reflector, a lamp-member, a socket-member having movement in said lamp-member in any direction along or about the line of the principal axis of said reflector, and resiliently acting position-retaining means continuously acting operatively upon said socket-member, said socket-member comprising a cylindrical portion provided with retardent surface-formations acted on retardingly to said movements of said socket-

member in any of said stated directions, and said resiliently acting position-retaining means provided with a coaxing surface.

5. In an electric lamp, the combination of a reflector, a lamp-member, a socket-member, a plug for the latter, spring-pressed connecting means between said socket member and plug arranged to be connected by axial and rotative movements of said plug, said socket-member having movement in said lamp-member in any direction along or about the line of the principal axis of said reflector, and resiliently acting position-retaining means continuously acting operatively upon said socket-member, said socket-member comprising a cylindrical portion provided with retardent surface-formations acted on retardingly to said movements of said socket-member, said resiliently acting positioning means provided with a coaxing surface, and a stop for limiting movement of said socket-member in the directions of said axial and rotative movements of said plug.

6. In an electric lamp, the combination of a reflector, a cylindrical flange about the line of the principal axis of said reflector, a socket-member therein guided thereby, said socket-member comprising a cylindrical portion in said flange provided with alternate closely adjacent protuberances and depressions extending in a plurality of directions about said cylindrical portion, a spring-band about said flange, said flange provided with an aperture, and said spring-band provided with a part extending through said aperture, said last-named part provided with a surface complementary to said protuberances and depressions, for manual movement of said socket-member in any direction along or about said line of said principal axis of said reflector.

7. In an electric lamp, the combination of a reflector, a cylindrical flange about the line of the principal axis of said reflector, a socket-member therein guided thereby, a plug for the latter, spring-pressed connecting means between said plug and socket-member arranged to be connected by axial and rotative movements of said plug, said socket-member comprising a cylindrical portion in said flange provided with alternate closely adjacent protuberances and depressions extending in a plurality of directions about said cylindrical portion, a spring-band about said flange, said flange provided with an aperture, and said spring-band provided with a part extending through said aperture, said last-named part provided with a surface complementary to said protuberances and depressions, for manual movement of said socket-member in any direction along or about said line of said principal axis of said reflector, and a stop for limiting movement of said socket-member.

in the directions of said axial and rotative movements of said plug during connecting of said plug.

8. In an electric lamp, the combination of
5 a reflector, a lamp-member, a socket-member
therein, said members extending lengthwise
of the line of the principal axis of said re-
flector, and a resiliently acting position-re-
taining part, said last-named part and said
10 socket-member provided with coacting sur-
faces comprising retardent surface-forma-
tions extending in a plurality of directions,
constructed and arranged for movement of
said socket-member in said lamp-member
15 axially, rotatively, or in a direction which is
the sum of said axial and rotative move-
ments, said socket-member comprising a

plug-securing portion, means for limiting
axial movement of said socket-member for
locating said socket-member in plug-attach-
ing position, and means for limiting rotative
movement of said socket-member when in
20 plug-attaching position, said last-named
means formed by providing one of said
members with a projection and the other of
25 said members with a coacting recess.

In testimony whereof, I have hereunto
signed my name in the presence of two sub-
scribing witnesses.

CHARLES HARRY FISCHER.
